UNITED STATES PATENT OFFICE.

JAMES F. ARTHUR, OF DICKSON CITY, PENNSYLVANIA.

CIRCULATING-TUBE CONNECTION.

Application filed January 12, 1925. Serial No. 2,033.

This invention relates to a circulating tube, particularly designed for use in domestic hot water tanks. These tanks are usually cylindrical in shape, and have the cold water inlet pipe and the hot water outlet pipe connected to the top of the tank. The inlet pipe is usually provided with an extension, herein termed a circulating tube, which extends downwardly within the tank, terminating near the bottom thereof, so that the fresh supply of cold water may pass downwardly through the hot water in the tank, and be discharged near the bottom of the tank without interfering with or becoming mixed with the hot water in the upper part of the tank.

The common practice among plumbers has been to make the extension or circulating tube from ordinary galvanized iron pipe, but this has not proved entirely satisfactory, owing to the fact that the iron, even though galvanized, will become corroded through continued contact with the hot water. When brass or copper pipe was used, however, it had to be of the same size and thickness as standard iron pipe, so that it could be cut and threaded with the standard plumbers' tools, and be assembled with standard connections. This made the job quite expensive, while the circulating pipe was much heavier than the service required.

The object of the present invention is to provide a tube for the purpose stated, which is made from the usual commercial brass or copper tubing, and provided at one end with a bushing having a standard thread, and held between a bead formed circumferentially of the tubing and a terminal flange which is swaged over the end of the bushing.

The invention will be more fully explained in connection with the accompanying drawing, in which

Figure 1 is a view illustrating the first step, which consists in forming a bead near one end of the tubing.

Figure 2 is a longitudinal section through a portion of the tube after the bead has been formed.

Figure 3 illustrates the manner in which the bushing is placed on the end of the beaded tube.

Figure 4 illustrates the step of swaging the end of the tube over the end of the bushing while the latter is held against the bead on the tube.

Figure 5 is a longitudinal section through the completed tube.

Figure 6 is a transverse section through a tube of modified construction, wherein knobs are substituted for the bead.

In carrying out the invention, I take a piece of light commercial brass or copper tubing 10, and place it over a revolving mandrel 11, having a circumferential knurled bead 12, as shown in Figure 1. Underneath the mandrel is a pivoted lever 13, having a fork 14 in which is journaled a roller 15, having a circumferential groove 16 adapted to mate with the knurled bead 12. When the lever is actuated to press the roller 15 against the mandrel, the wall of the tubing 10 is drawn out to form a circumferential bead 17, as shown in Figure 2. In this step of the process, the knurled surface of the bead 12 on the mandrel engages the inner face of the tube, and causes the latter to revolve with the mandrel, so that a uniform bead 17 is formed in the tube.

A brass bushing 18 is now placed over the end of the beaded tube, as shown in Figure 3, with its polygonal head 19 abutting against the bead 17. This bushing is formed with standard threads 20, and its inner end is reamed out to form an internal outwardly inclined shoulder, as shown at 21, before being placed on the tubing. The bead 17 is formed at the proper distance from the end of the tubing, so that the latter projects through and slightly beyond the shoulder 21 of the bushing.

The tube 10 with the bushing thereon is now placed in a vise 22, in front of a spinning tool 23, which is secured in a spinning arbor 24, slidably mounted in a bronze bearing 25. The spinning tool 23 is formed with a beveled shoulder 26, which is adapted to engage the end of the tubing 10 and swage it over the shoulder 21 of the bushing, forming a flange 27, as shown in Figure 5. During this step in the process, the bead 17 forms an abutment against which the bushing is held until the swaging operation is completed, and the bushing becomes, in effect, an integral part of the tube.

Since the function of the bead 17 is merely that of an abutment, its particular shape is not important. In Figure 6, I have shown a modification in which a tube 28, similar to the tube 10, is formed with a plurality of outwardly pressed knobs 29, which, for the

purposes of the present invention, are the equivalent of the bead 17. These knobs may be made by the use of a press with a male and female die. Instead of the abutments 5 17 or 29, abutments of solder could be used in their place.

It will be noted that the internal diameter of the bushing is substantially the same as the external diameter of the body of the 10 thin-walled tube, so that there is no lessening of diameter of the tube and consequent constriction of flow.

It will be understood, of course, that the usual commercial brass or copper tubing is so 15 light and thin that it is impossible to thread it without cutting through the wall, or so weakening it that it can not be used. The present invention provides a practical method for reinforcing the end of such a tube, 20 and providing it with standard threads, so that it may be used for the purpose stated without any needless expense, and for all practical purposes it will be just as durable, or even more durable than a brass or copper 25 pipe having the same size and thickness as a standard iron pipe.

While I have described the invention specifically with reference to its use in connection with the installation of hot water tank, 30 it will be obvious that the invention is capable of other uses, and that other modifications may be made therein without departing materially from the essential features of the invention. It is, therefore, my intention to 35 include all such uses and modifications within the scope of what is claimed. Where an absolutely water or air tight joint is desired, the bushing may be soldered, brazed, or welded to the tube.

40 What is claimed is:

1. A circulating tube for hot water boilers comprising in combination a thin walled tube of uniform wall thickness throughout,

provided with an outwardly extending shoulder portion forming an abutment, and 45 a bushing of heavier metal positioned on one end of the tube, said abutment being spaced in from the end of the tube a distance equal to the length of the bushing, the end of the tube being expanded outwardly into engagement 50 with the bushing, the abutment being positioned just beyond the inner end of the bushing and bearing against the extreme inner end of the bushing for holding the bushing in place on the tube, the bushing 55 being exteriorly threaded and provided exteriorly with a portion to which a wrench may be applied, the threaded portion and the wrench receiving portion being located between the expanded end of the tube and 60 the abutment.

2. A circulating tube for hot water boilers comprising in combination a thin walled tube of uniform wall thickness throughout, 65 provided with an outwardly extending shoulder portion forming an abutment, and a bushing of heavier metal positioned on one end of the tube, said abutment being spaced in from the end of the tube a distance equal to the length of the bushing, the outer end 70 of the bushing being provided with an annular, outwardly inclined shoulder, the end of the tube being expanded outwardly into engagement with said annular shoulder, the abutment being positioned just beyond 75 the inner end of the bushing for holding the bushing in place on the tube, the bushing being exteriorly threaded and provided exteriorly with a portion to which a wrench may be applied, the threaded portion and the wrench receiving portion being located between the expanded end of the tube and 80 the abutment.

In testimony that I claim the foregoing as my own, I have hereto affixed my signature.

JAMES F. ARTHUR.
